CLAIM

The ornamental design for a massage gun, as shown and described.

DESCRIPTION

FIG. 1 is a front elevation view of a massage gun showing our new design.

FIG. 2 is a rear elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a perspective view thereof.

FIG. 8 is a front elevation view of the design in an alternate configuration of use.

FIG. 9 is a rear elevation view thereof.

FIG. 10 is an enlarged left side elevation view thereof.

FIG. 11 is an enlarged right side elevation view thereof.

FIG. 12 is a top plan view thereof.

FIG. 13 is a bottom plan view thereof.

FIG. 14 is a perspective view thereof.

FIG. 15 is a front elevation view of the design in another alternate configuration of use.

FIG. 16 is a rear elevation view thereof.

FIG. 17 is an enlarged left side elevation view thereof.

FIG. 18 is an enlarged right side elevation view thereof.

FIG. 19 is a top plan view thereof.

FIG. 20 is a bottom plan view thereof; and,

FIG. 21 is a perspective view thereof.

The broken lines in the drawings depict portions of the massage gun that form no part of the claimed design.
